UNITED STATES PATENT OFFICE.

URAL STILWELL TRAUB, OF YONKERS, NEW YORK.

VALVE MECHANISM FOR EXPLOSIVE-ENGINES.

1,089,989.

Specification of Letters Patent. Patented Mar. 10, 1914.

Application filed March 13, 1912. Serial No. 683,474.

To all whom it may concern:

Be it known that I, URAL STILWELL TRAUB, a citizen of the United States, residing at Yonkers, in the county of Westchester and State of New York, have invented certain new and useful Improvements in Valve-Mechanism for Explosive-Engines, of which the following is a specification.

The primary object of this invention is to simplify the construction of valve mechanism for internal combustion engines comprising a plurality of cylinders.

In carrying out the invention, it is contemplated to utilize a valve casing associated with all of the cylinders of the engine and having suitable ports communicating therewith, there being mounted in said casing a pair of sliding valves, one inclosing the other and both having a peculiar arrangement of exhaust and intake ports whereby in a single complete stroke of the valve mechanism, as designed for a four-cylinder engine, each cylinder will be allowed to exhaust and intake twice.

A further object of the invention has been to employ an exceedingly simple operating means for controlling the movements of the valves in relation to one another, and their movement in relation to the exhaust and intake ports of the cylinders and to the corresponding ports of exhaust and intake manifolds. Said operating means comprises a single shaft operated from the engine shaft and directly connected with the valves so as to reciprocate the latter in a proper manner in order to perform the desired result.

While the invention, as hereinafter set forth, is used in connection with a four-cylinder engine, it will be evident that the principles of construction and operation thereof may be used equally well for motors comprising two or more cylinders, all of which will be more fully comprehended upon reference to the following detail description and to the accompanying drawings, in which—

Figure 1 is a side elevation of an ordinary four-cycle internal combustion engine, illustrating the invention applied thereto, the detachable end of the valve casing being shown in section to bring out clearly the connections of the operating shaft with the valves. Fig. 2 is a fragmentary view, partly in section and illustrating fully the manner in which the operating shaft is geared to the

engine shaft. Fig. 3 is a sectional view partly broken away and illustrating the gearing and shaft connections in end elevation in their positions as seen in Fig. 2. Fig. 4 is a plan view of the valve casing. Fig. 5 is a plan view of the outer sliding valve. Fig. 6 is a view similar to Fig. 5, showing the inner sliding valve. Fig. 7 is a longitudinal sectional view through the valve mechanism proper, and taken about on the line 7—7 of Fig. 8. Fig. 8 is a transverse section taken about on the line 8—8 of Fig. 7.

Throughout the following detail description and on the several figures of the drawings, similar parts are referred to by like reference characters.

As shown in Fig. 1, a conventional type of four-cylinder engine has the invention applied thereto, the respective cylinders being denoted 1, 2, 3 and 4, the crank casing 5, the fly-wheel 6, and the crank or motor shaft 7. Mounted in a suitable extension 5' of the crank casing 5 is the vertical operating shaft 8 having the bevel gear 9 on its lower end arranged to mesh with a bevel gear 10 secured to the engine shaft 7 which rotates in a clock-wise direction. In order that the operating shaft 8 may actuate the valves properly, the shaft 7 is geared to the shaft 8, in a ratio of one to four, or in other words, the shaft 8 makes a complete revolution during four complete revolutions of the shaft 7. At its upper end portion, the shaft 8 is mounted in suitable bearings in the detachable end A' of the valve casing A and projecting from the shaft 8, within the part A' of the casing A are cranks 11 and 12, the crank 11 being connected by a pitman rod 13 with the hollow sleeve-like valve B, whereas the crank 12 is similarly connected by the rod 14 with a second valve C which is mounted in the valve B. Each of the valves B and C is formed with an extension 15 with which its co-operating pitman rod is connected and nuts 16 may be screwed on the ends of said extensions 15 to prevent displacement of the pitman rods from said extensions. The valve casing A may be provided with flanges A'' at its opposite sides to facilitate bolting or fastening said casing to the cylinders 1, 2, 3 and 4 at the upper ends of the latter, and said casing A is formed at its lower end with four intake ports x and four exhaust ports y that regis-

ter with corresponding ports x' and y' of the cylinders to establish communication between the valve casing and cylinders, as controlled, however, by the positions of the valves B and C which also have ports to register with the ports x and y . The casing A has at its upper portions four intake ports x'' and four exhaust ports y'' which lead into an intake manifold 17 and an exhaust manifold 18, respectively, the former leading to a carburetor, not shown, and the latter to a suitable point of exhaust for the motor.

The arrangement of the intake and exhaust ports of the valves B and C being peculiar, will be specifically described. As shown in Figs. 5 and 6, the valve B has the intake ports a , b , c , d , e , f and g , and the exhaust ports a' , b' , c' , d' , e' , f' and g' . The valve C has the intake ports h , i , j , k , l , m and o , and the exhaust ports h' , i' , j' , k' , l' , m' and o' . The intake and exhaust ports of the valve B are in reality located at opposite, or the upper and lower sides of said valve and are constituted by two openings in the valve, whereas, with respect to the valve C, the intake and exhaust ports are each a single opening leading entirely through the valve so as to register at proper times with the opposite openings of the valve B, a pair of which constitutes each port of the latter valve. For the purposes of this description, however, the two openings constituting each port of the valve B are considered a single port.

The arrangement of the cranks 11 and 12 is such that the crank 11 is located 45 degrees, or about one inch in advance of the crank 12 if the stroke of the cranks is about four inches. The manner in which the various ports of the valves B and C are caused to register with each other and with the proper intake and exhaust ports of the several cylinders of the engine during a complete stroke of said valves under the action of the shaft, will now be described.

Referring to Fig. 7, on the basis of a full valve stroke of four inches from right to left, in the outstroke of the valves, moving to the left as shown in the drawings, when valve B has progressed about one and one-half inches its crank 11 will have moved $67\frac{1}{2}$ degrees in the direction mentioned, and valve C one-half inch and its crank 12 about $22\frac{1}{2}$ degrees. The positions assumed now are seen in Figs. 1, 2, 3 and 7, and this allows cylinder 1 to exhaust and cylinder 2 to intake, respectively, by registration of the exhaust ports a' and h' , and the intake ports c and i . The next registration is of ports b and h , permitting cylinder 1 to intake, and of ports e' and l' , permitting cylinder 3 to exhaust. The following registrations of ports then occur in regular order. Ports g and l permit cylinder 3 to intake,

and ports g' and o' permit cylinder 4 to exhaust; while valve B completes its instroke and advances $67\frac{1}{2}$ degrees on its return stroke and valve C is finishing its instroke and advances $22\frac{1}{2}$ degrees on its return stroke, cylinder 4 intakes through ports g and o , and cylinder 2 exhausts through ports c' and k' ; cylinder 2 then intakes through ports e and j , and cylinder 1 exhausts through ports a' and i' ; cylinder 1 then intakes through ports a and h , and cylinder 3 exhausts through ports d' and l' ; while valve B is moving to the end of its return stroke and starting again on its outstroke, and valve C is still moving in its instroke, cylinder 3 intakes through ports d and k , and cylinder 4 exhausts through ports f' and m' ; again, as valve B moves on the outstroke to the point at which its movement was taken up in this description, and as valve C is likewise moving to a corresponding position, cylinder 4 intakes through ports f and m , and cylinder 2 exhausts through ports b' and j' . A complete stroke of each valve is completed after all of the foregoing registrations of the ports of the valves with each other, and, of course, with the corresponding intakes and exhausts of the cylinders named, have taken place. In the above operation all of the cylinders have exhausted, intaken, compressed, and exploded twice during the complete stroke of the valves.

It is contemplated to provide suitable packing rings between the valves B and C and the casing A in order to facilitate a proper operation of these valves in controlling the passage and exhaust of the motive fluid through the valve mechanism. If desired, the valve casing A may be water-jacketed in the manner illustrated in Fig. 2 and in so far as certain details of construction including the special connections between the parts are concerned, it will be understood that considerable modification may be made in the reduction of the invention to practice.

The valve mechanism, as above described, eliminates the necessity of providing separate valves for the various cylinders of the engine, and affords many practical advantages over the common type of valve mechanism for explosive motors, wherein separate valves are used for each cylinder to control the intake and exhaust.

Having thus described the invention, what is claimed as new is:

1. In a multiple cylinder explosive engine, the combination of a valve casing having intake and exhaust ports communicating with each cylinder, a tubular valve mounted in said casing and having intake and exhaust ports corresponding with those of the casing, each of the last mentioned ports being constituted by aligned openings in opposite

sides of the walls of the valve, a second valve mounted in the first mentioned valve and having transverse dimensions proportioned to cause the second valve to snugly fit within the first valve, the second valve having intake and exhaust ports leading entirely therethrough to register with the corresponding ports of the first valve, the ports of the second valve being surrounded throughout their length with the material of the valve, and means for actuating said valves both relative to each other and to the casing for effecting properly timed registration of the respective ports.

2. In combination, a multiple cylinder explosive engine, a valve casing having intake and exhaust ports communicating with each cylinder, a hollow valve mounted in said casing and having intake and exhaust ports to correspond with those of the casing, each of the last mentioned intake and exhaust ports being constituted by openings at opposite sides of the valve, a second valve mounted in the first mentioned valve and having intake and exhaust ports leading entirely therethrough to register with the corresponding ports of the first mentioned valve and the casing, and means for actuating said valves from the engine shaft to impart relative movement thereto, and movement to the valves relative to the ports of the casing.

3. In combination, a multiple cylinder explosive engine, a valve casing having intake and exhaust ports communicating with each cylinder, a hollow valve mounted in said casing and having intake and exhaust ports to correspond with those of the casing, each of the last mentioned intake and exhaust ports being constituted by openings at opposite sides of the valve, a second valve mounted in the first mentioned valve and having intake and exhaust ports leading entirely therethrough to register with the corresponding ports of the first mentioned valve and the casing, and means for reciprocating said valves, one within the other to cause registration of their ports at proper inter-

vals and to cause their ports to register with the ports of the valve casing. 50

4. In combination, a multiple cylinder explosive engine, a valve casing having intake and exhaust ports communicating with each cylinder, a hollow valve mounted in said casing and having intake and exhaust ports to correspond with those of the casing, each of the last mentioned intake and exhaust ports being constituted by openings at opposite sides of the valve, a second valve mounted in the first mentioned valve and having intake and exhaust ports leading entirely therethrough to register with the corresponding ports of the first mentioned valve and the casing, an operating shaft geared to the shaft of the engine, and cranks on said shaft connected with the respective valves aforesaid to cause such relative movement of the latter as to permit each cylinder to intake and exhaust in regular order. 60

5. In combination, a four-cylinder explosive engine, a valve casing having intake and exhaust ports communicating with each cylinder of said engine, intake and exhaust means connected with said casing, a hollow valve slidably mounted in the casing and having intake and exhaust ports therein, each port of the hollow valve being constituted by openings at opposite sides thereof, a second valve mounted to slide in the hollow valve and having intake and exhaust ports corresponding with those of the hollow valve, an operating shaft geared to the shaft of the engine in the ratio of four to one, and connections between the shaft and the said valves, whereby, during a complete revolution of the operating shaft, the valves will be moved relative to one another and relative to the intake and exhaust ports of each cylinder to cause each cylinder to intake and exhaust twice. 70 75 80 85 90
